UNITED STATES PATENT OFFICE.

CHARLES J. W. ADDISON, OF CHELSEA, MASSACHUSETTS.

DESIGN FOR A SPOON.

SPECIFICATION forming part of Design No. 20,689, dated April 28, 1891.

Application filed March 31, 1891. Serial No. 387,191. Term of patent 7 years.

To all whom it may concern:

Be it known that I, CHARLES J. W. ADDISON, a citizen of the United States, residing at Chelsea, in the county of Suffolk and State of Massachusetts, have invented and produced a new and original Design for the Handles of Spoons and other Flat Ware, of which the following is a specification, reference being had to the accompanying drawing, forming a part thereof, in which the figure represents a face view of a spoon embodying my new design in the handle thereof.

The leading feature of my design consists in the figure of an Indian on a ground representing a shield-like figure.

The letter *a* indicates the figure of the Indian, and *b* the shield-like figure which ranges longitudinally of the handle, the side marginal line *b'* of the figure *b* being in the form 20 of an irregular curve and the opposite marginal line *b''* being in the form of an irregular compound curve, the said marginal lines ter-

minating at the bottom in a scroll *b''*. The shield is surmounted by the figure *c*, representing a powder-horn. ²⁵

The letter *d* indicates the representation of a rope as laced through the shield and ranging thence forwardly of the handle and formed into double loops *d'*.

The minor features mentioned are immaterial, the essential feature being the figure of the Indian on a ground in the form of a shield-like figure.

On the powder-horn appears the word "Chelsea," and on the handle the word "Win-³⁵ nisimmet;" but such words form no part of my design.

I claim—

The design for the handles of spoons and similar ware, as herein shown and described. ⁴⁰

CHARLES J. W. ADDISON.
